UNITED STATES PATENT OFFICE.

WILLIAM GILBERT CHENEY, OF MARLBORO, MASSACHUSETTS, ASSIGNOR TO UNITED SHOE MACHINERY CORPORATION, OF PATERSON, NEW JERSEY, A CORPORATION OF NEW JERSEY.

COATING APPARATUS.

Application filed September 13, 1919. Serial No. 323,495.

To all whom it may concern:

Be it known that I, WILLIAM G. CHENEY, a citizen of the United States, residing at Marlboro, in the county of Middlesex and 5 State of Massachusetts, have invented certain Improvements in Coating Apparatus, of which the following description, in connection with the accompanying drawings, is a specification, like reference characters 10 on the drawings indicating like parts in the several figures.

My invention relates to apparatus for applying fluid coating to such objects as shoes. More especially is it designed for 15 cementing shoes of the tennis type for the application of their foxings and soles.

Objects of the invention are to provide an apparatus in which a plurality of surfaces may be coated simultaneously and the 20 application made accurately along predetermined lines. For example, the bottoms and adjacent edges of the uppers of tennis shoes are coated at the same time and the top line of the foxing area cleanly cut.

25 In the accomplishment of these objects, a feature of the invention consists of a yieldable applying member, as a brush, within which is carried means, as a gage disk situated between the fibers of the brush, to 30 determine the marginal line along which coating is to be applied to the work. By this arrangement, when the work, for example the lasted upper of a shoe, is forced into the fibers, both the bottom and the edges 35 above said bottom are coated, the latter to a height determined by the space between the peripheries of the brush and gage.

To facilitate the proper application of the coating to shoes, so that excessive pressure 40 shall not be required to effect the coating of the edges as well as the bottoms, there is furnished as another feature of the invention an applying member in which is a depression approximating in depth the height 45 of the foxing line above the shoe bottom. Preferably the width of this depression is that of a relatively narrow portion of the shoe bottoms to be cemented. By this arrangement application to all the foxing 50 surface is assured.

As a further feature of the invention, I have a member for contact with the work extending along the rotatable brush or other 55 applying member in the same direction as the axis of rotation, the opposite extrem-

ities of the contact member being variable in their relation to the axis of the applying member. This contact member may be a work-supporting roll and may cooperate with an applying brush the axis of rotation of which is horizontal. By separate vertical adjustment of the ends of this roll, the work advancing over it may be presented to the brush in the desired relation.

Other features will be hereinafter developed, reference being had to the accompanying drawings, in which,

Fig. 1 is a side elevation of one embodiment of the invention;

Fig. 2 is an end elevation looking from 70 the left in Fig. 1, with a portion broken away; and

Fig. 3 is a detail in elevation of the brush with the upper portion in section.

In bearings 10 near the top end walls 75 of a suitable trough-like receptacle 12 is journaled a shaft 14, carrying fast and loose pulleys 16 to which power may be applied from a suitable source by a belt, not illustrated. Within the receptacle there is 80 secured to the shaft by set screws 18 an applying member A. This is shown as consisting of a cylindrical core 20 between end flanges 22, 22 on which are situated radial tufts of fibers 24, the outer ends of which 85 present a generally cylindrical surface dipping in the body of cement or other coating fluid contained in the receptacle, and bringing it up for application to the work pressed against the upper ends of the fibers. Ex- 90

tending about the brush near its longitudinal center is shown a depression 26 formed by fibers of less length than those upon each side of the depression. The depth of the depression 26 is preferably somewhat less 95 than the height to which the coating fluid is to be applied to the edge of the upper of the shoe operated on. As to its width, the depression may be substantially that of the narrowest central portion of the shoe, con- 100 sidered at the foxing area, so that the longer fibers at each side of the depression may with certainty contact with this portion, yet may be deflected laterally and maintain their contact with the wider parts. The length 105 of the fibers should be sufficient to permit this yield without their rubbing too heavily upon the work and thus tending to brush off the applied fluid.

Fixed to the core between the tufts of 110

fibers in the depressed portion, I have shown means for limiting the amount which the work can be pressed into the brush. This may consist of disks 28, 28 of some such thin material as sheet metal and of a diameter a little less than the portion 26 of the brush. The difference between the peripheries of these gage disks and the portions of the brush of greater diameter at each side of the depression should be substantially equal to the width of the foxing area, while the projection of the fibers in the depressed portion beyond the disks should be such as to assure the proper brushing on of the coating fluid to the bottom of the shoe. As illustrated, the disks are symmetrically arranged at each side of the center of the depression, furnishing a stable support for the work without tendency to tip laterally when it bears against them.

Preferably at opposite sides of the brush just within the edges of the receptacle walls, there extend parallel to the axis of rotation contact members furnished by rolls 30 and 32. The upper edges of these rolls are substantially alined in a horizontal plane with the upper points of the gage disks, so that the work will be supported for advance in a straight line as it is pressed across the rolls and brush. The roll 32, which is at the forward side of the brush, in addition to its work supporting function may also serve by contact with the bottom of the shoe to remove therefrom any excess of the applied fluid. The rolls are journaled at their ends in bearing plates 34, preferably fixed to a supporting bar 36 for the rear roll and a rod 38 for the forward roll, by screw and vertical slot connections 40. By independent adjustment of the end bearings of the rolls their angle to the horizontal may be altered, until they so contact with the curved shoe bottoms that these are best presented to the brush to attain uniformity of the upper foxing line. The bar 36, as illustrated, is fixed rigidly to the top of the receptacle, but the rod 38 is hinged at 42, allowing the roll 32 to be turned back clear of the receptacle, giving access to it for the introduction of the coating material. The receptacle may be emptied when desired by the removal of a plug 43, normally closing an opening in an end wall of the receptacle near the bottom.

Beneath the roll 30, between the ends of the receptacle, extends a rod 44, and partly surrounding this is a scraper 46, which may be of spring material with its upper edge bearing against and preferably conforming to the outline of the periphery of the brush. Projecting upwardly and rearwardly from the scraper is an arm 48 at the upper end of which is an opening to receive a screw 50 threaded through the wall of the receptacle,

this screw having fixed to it at each side of the arm collars 52. By rotating screw 50, the scraper may be turned about the rod 44 so that its engaging edge may be varied in its relation to the brush to remove therefrom more or less of the coating fluid. This enables the operator to change the amount brought up for application to the work.

In using the apparatus for applying cement to such work as the bottom and lower edge of the upper of a lasted shoe, as is illustrated at S in Fig. 3 of the drawings, the operator presents the work with one extremity, as the toe, to the brush in a position downwardly inclined to the horizontal, the bottom resting upon the roll 30. It is forced into the brush sufficiently to coat the foxing area at the end of the toe, and then advanced over the brush and simultaneously swung downwardly upon the roll 30. The shoe in its travel now rests upon this roll and the disks 28, the bottom being cemented by the brush fibers of the depressed portion 26 and the edges of the fibers of the elevated side portions contacting with the foxing area to coat this, the marginal line of the coated portion being fixed by the radial distance between the peripheries of the disks and the ends of the fibers. Thus there is correspondence between a characteristic of the coated area, in the present instance the width, and the relation, radially of the brush, of the peripheries of the gage-disks to the ends of the brush-fibers furnishing the elevated portions. These fibers yield as the shoe widens and return to their original positions as the narrower shank portion is reached. In this advance the work passes upon the roll 32, which maintains the horizontal position of said work after the heel portion has left the roll 30. When the heel reaches the forward side of the brush, the work is again tilted but oppositely to that of the presentation of the toe, thus coating the foxing area at the extremity of the heel.

Having described my invention, what I claim as new and desire to secure by Letters Patent of the United States is:

1. In a coating apparatus, a yieldable applying member, and means carried within the applying member and arranged to determine the marginal line along which the coating is to be applied to the work.
2. In a coating apparatus, a yieldable applying member, and gage means carried within the applying member and arranged in a relation to the applying surface in accordance with a characteristic of the coating to be applied to the work.
3. In a coating apparatus, a yieldable applying member, and gage means carried within the applying member and arranged at a distance from its surface substantially

equal to the height to which the coating is to extend upon the work.

4. In a coating apparatus, a rotatable brush, and a gage disk situated between the fibers of the brush with its periphery arranged with reference to the brush surface to determine the area to which the coating is to be applied.

5. In an apparatus for cementing the bottoms and adjacent portions of the uppers of shoes for the application of the soles and foxings, a rotatable brush, and a gage disk situated between the fibers of the brush with its periphery arranged with reference to that of the brush to determine the height of the foxing line above the shoe bottom.

6. In an apparatus for cementing the bottoms and adjacent portions of the uppers of shoes for the application of the soles and foxings, a cylindrical brush having a peripheral depression, the depth of the depression approximating the height of the foxing line above the shoe bottom to be cemented.

25 7. In an apparatus for cementing the bottoms and adjacent portions of the uppers of shoes for the application of the soles and foxings, a cylindrical brush having a peripheral depression, the width of the depression approximating a narrower portion of the shoe bottom to be cemented.

35 8. In an apparatus for cementing the bottoms and adjacent portions of the uppers of shoes for the application of the soles and foxings, a cylindrical brush having a peripheral depression, the depth of the depression approximating the height of the foxing line above the shoe bottom to be cemented and the width of the depression approximating a narrower portion of the shoe bottom to be cemented.

40 9. In an apparatus for cementing the bottoms and adjacent portions of the uppers of shoes for the application of the soles and foxings, a cylindrical brush having a peripheral depression, the depth of the depression approximating the height of the foxing line above the shoe bottom to be cemented, and means arranged to limit the extent to which the shoe may be forced into the brush.

55 10. In a coating apparatus, a cylindrical brush having a peripheral depression, and a gage disk carried within the depressed portion of the brush.

11. In a coating apparatus, a cylindrical brush having a peripheral depression, and gage disks symmetrically spaced from one another within the depressed portion of the brush.

60 12. In a coating apparatus, a rotatable applying member, a contact member for the work extending along the applying member in the same direction as the axis of rotation, and means arranged to vary independently

the relation of the opposite extremities of the contact member to the axis of the applying member.

13. In a coating apparatus, a rotatable applying brush, and a work-supporting roll contacting with the brush.

14. In a coating apparatus, a rotatable applying brush, a work-supporting roll contacting with the brush, and bearings for the ends of the roll arranged for independent adjustment.

15. In a coating apparatus, an applying brush rotatable about a horizontal axis, a work-supporting roll co-operating with the brush, and means arranged to vary the vertical position of the roll.

16. In a coating apparatus, an applying brush rotatable about a horizontal axis, a work-supporting roll co-operating with the brush, and independent means arranged to vary the vertical position of the ends of the roll.

17. In a coating apparatus, a rotatable applying brush, work-supporting rolls situated at opposite sides of the brush, and means arranged to vary the relation between the rolls and brush.

18. In a coating apparatus, a rotatable applying brush, and work-supporting rolls situated at opposite sides of the brush, one of said rolls contacting with the brush.

19. In a coating apparatus, a rotatable applying brush, rolls co-operating with opposite sides of the brush, and means arranged to vary the vertical positions of the rolls.

20. In a coating apparatus, a rotatable applying brush, rolls co-operating with opposite sides of the brush, and means arranged to vary independently the vertical positions of the opposite ends of the rolls.

21. In an apparatus for cementing the bottoms and adjacent portions of the uppers of shoes for the application of the soles and foxings, an applying member having a depression between adjacent elevated portions, the depth of the depression approximating the height of the foxing line above the shoe bottom to be cemented.

22. In a coating apparatus, an applying brush, gage means associated with the brush, and work-supporting members situated at opposite sides of the brush, the gage means and work-supporting members bearing to each other a predetermined relation.

23. In a coating apparatus, a rotatable applying brush, gage-disks carried by the brush, and work-supporting rolls situated at opposite sides of the brush, the peripheries of the disks and rolls being substantially alined.

In testimony whereof I have signed my name to this specification.

WILLIAM GILBERT CHENEY.
